UNITED STATES PATENT OFFICE

FRANK R. WALLACE, OF PHILADELPHIA, PENNSYLVANIA, ASSIGNOR TO THE TABOR MANUFACTURING COMPANY, OF PHILADELPHIA, PENNSYLVANIA, A CORPORATION OF PENNSYLVANIA

CHOCK AND STARTER FOR MOLDING MACHINES

Application filed June 21, 1928. Serial No. 237,923.

The present invention is intended for application to molding machines in which a flask receiving means is mounted upon a truck or car which, traveling on the rails of a tramway, is run into and out of the molding machine and is utilized to hold and support the flask during the pattern drawing operation. It is essential that the truck remain at rest during the pattern drawing operation in order to insure perfect molds or half molds.

It is the principal object of the present invention to provide simple, reliable and efficient chock mechanism for automatically engaging and firmly holding the truck in position in the machine and for, upon manual release, starting the truck out of the machine by the action of a spring previously compressed in arresting the incoming movement of the car or truck.

Generally stated, the invention may be said to comprise a rocking shoe having a shank and of which one end is always above the rail of the tramway and of which the other end is adapted to move above and below the same, a stop for the shoe when its last named end is below the rail, an extension spring coupling pivotally anchored at one end and pivotally connected at the other end to said extension and adapted to normally turn said shoe up to its stop, a pivotal lever having a catch for automatically engaging said extension and for releasing the same, and a spring for said lever.

The invention also comprises the improvements to be presently described and finally claimed.

In the following description reference will be made to the accompanying drawings forming part hereof and in which

Figure 1 is a side view of a chock and starter embodying features of the invention showing in dotted lines and in full lines two positions of the shoe and also showing a wheel of a tram car.

Fig. 2 is an end view looking from left to right in Fig. 1 and showing the rail of the tramway in section.

Referring to the drawings 1 is a rocking shoe adapted in the position shown in full lines in Fig. 1 to present both of its ends 2

and 3 above the rail indicated by the line 4 in Fig. 1 and in position for engagement with the wheel flange 5. The rocking shoe in the position shown in dotted lines presents the end 2 below the rail and the end 3 above the rail in position for engagement with a wheel flange traveling from right to left in Fig. 1. 6 is a stop and 7 is a spring arranged to urge the end 2 of the shoe into contact with the stop and into the position shown by dotted lines, and the spring operates to start the car of the tramway from left to right in Fig. 1. The shoe is shown as rocking about the pivot 8' provided on a base 8, and the spring is shown in the form of an extension spring coupling of which the end 9 is pivoted to the base by a pivot 10, and of which the end 11 is pivoted to an extension 12 provided on the shoe. There is a hand lever 13 pivoted at 10 and having a catch 14 for engaging the extension 12 and for releasing the same. As shown the catch 14 engages the pin 15 projecting from the extension 12, and this pin 15 also serves for pivotal connection with the end 11 of the coupling.

16 is a spring connected with the hand lever 13 and with the base 8, and its purpose is to yieldably hold the lever up to the extension 12, or more accurately, up to the pin 15 projecting from the extension 12.

The mode of operation may be described as follows:

Assuming the shoe to be in the position shown in dotted lines, the pin 15 is clear of the catch 14, and the hand lever is turned toward the right from the position that it occupies in Fig. 1 under the action of the spring 16, so that it rides upon the pin 15, but the catch 14 is well below the pin 15. The parts are not shown in that position because it would confuse the drawings and because it is believed that the matter will be readily understood from the foregoing description. When the truck is pushed into the molding machine in which the chock and starter are arranged, the flange 5 of the oncoming wheel rides above and past the end 2 of the shoe but strikes the end 3 of the shoe and turns the shoe into the position shown by full lines, compressing the spring 7. This movement of

the shoe brings the pin 15 under the catch 14 which automatically locks the shoe and wheel so that the latter is immovable while a pattern is drawn. Reference has been made to the ends of the shoe but some might de-
5 scribe the parts referred to as pads. Upon completion of the pattern drawing operation the operator pulls the handle 13 toward the left thus disengaging the catch from the pin 15. The spring 7 elongates the spring cou-
10 pling turning the shoe into dotted line position against its stop 6 and starting the car out of the molding machine. The spring 16 causes the hand lever to follow the pin 15 into position for re-engaging it.

15 It will be obvious to those skilled in the art to which the invention relates that modifications may be made in details of construction and arrangement and matters of mere form without departing from the spirit of the invention which is not limited to such matters or otherwise than the prior art and the appended claims may require.

I claim:

25 1. A chock and starter for molding machine tramways including, in combination, a rocking shoe adapted in one position to present both its ends above the rail and in position for engagement with the wheel 30 flange of a tramway and adapted in the other position to present one end below the rail and the other end above the rail in position for engagement with the wheel flange, a stop and a spring arranged to urge the shoe into contact with the stop and into the last named 35 position to start the car of the tramway, and a spring catch adapted to automatically lock the shoe when turned into the first mentioned position by the wheel flange of an oncoming 40 tram car and to release the shoe for spring action in starting the car.

45 2. A chock and starter for molding machine tramways comprising, in combination, a rocking shoe having a shank and of which one end is always above the rail and of which the other end is adapted to move above and below the same, a stop for the shoe when its last named end is below the rail, an extension 50 spring coupling pivotally anchored at one end and pivotally connected at the other end to said shoe and adapted to turn said shoe up to its stop, a pivotal lever having a catch for automatically engaging said extension and for releasing the same, and a spring for said 55 lever.

60 3. A chock and starter for molding machine tramways comprising, in combination, a rocking shoe having a shank and of which one end is always above the rail and of which the other end is adapted to move above and below the same, a stop for the shoe when its last named end is below the rail, an extension 65 spring coupling pivotally anchored at one end and pivotally connected at the other end to said shoe and adapted to turn said shoe up

to its stop, a lever pivoted concentrically with said coupling and having a catch for automatically engaging said extension and for releasing the same, and a spring for said lever.
